UNITED STATES PATENT OFFICE

1,928,110

BRUSH

Philip Mednick, Brooklyn, N. Y.

Application July 30, 1932. Serial No. 626,453

7 Claims. (Cl. 15—128)

This invention relates to new and useful improvements in brushes, and constitutes a further improvement of the invention for which application for patent has been filed by me April 9, 1932, under Serial No. 604,191.

The present device has a wide scope of use, as it may with advantage be employed in connection with bathing, dishwashing, auto-washing, and for other similar purposes.

10 As the construction is comparatively simple, the cost of manufacturing should be proportionately low.

With the above and other objects in view, this invention consists of the novel features of construction, combination and arrangement of parts, hereinafter fully described, claimed and illustrated in the accompanying drawings forming part of this specification, and in which similar characters of reference indicate corresponding parts in all views, and in which:

Figure 1 is bottom view of my device. Figure 2 is a transverse sectional view, taken on the line 2—2 of Figure 1. Figure 3 is a side view of a section of the brush, showing the relative arrangement and manner of securing the bristles. Figure 4 is an edge view of Figure 3. Figures 5 and 6 show in detail the inlaid metal-tubes; the one of these being slightly varied in construction from the other one, but not in principle. Figure 7 shows an edge view of the end portions of my device, which in this case has been slightly modified. Figure 8 is a cross sectional view of another form of my device; while Figure 9 shows a bottom view of the latter with the sponges, employed in this modification, removed; and Figure 10 represents a bottom view of the removable center part of the brush-device, according to the latter modification; while Figure 11 is a detail view.

Referring more particularly to the drawings, 40 10 indicates a preferably wooden member, or block, of any suitable shape, having a substantially flat bottom surface 11, and with provisions made at its top, in the form of a recess 12, to engage a handle. The said block has upon its bottom surface the usual arrangement of bristles 13. The block member is formed with a circumferentially cut-out, or reduced portion 14 of any convenient shape. In the said cut-out portion is mounted a tube 15 of any suitable material and of a form preferably as shown in the Figures 5 and 6; generally a metal tube would best serve the purpose in mind. The said tube may either consist of one unit, as shown in Figure 5, wherein 50 one end of the said tube is closed as at 16, while the other end is formed with an elongated arm 17

adapted to receive thereon a rubber hose, for which latter purpose the said arm has further been provided with an enlargement 18 near its end; the said hose being in turn connected to a water source,—or a slight modification may be resorted to, as shown in Figure 6, wherein the tube is ring-formed and with a separate faucet-arm 17, serving a similar purpose as in Figure 5, screwed into the said tube. The said tubes are in both cases provided at intervals with apertures 20 at their bottom side for the spraying of water.

In mounting the said metal tube in the block member, it may be necessary, in case the tube system shown in Figure 5 is used, to cut out in addition to the circumferential portion 14 also 70 a front portion of the block member; said additional portion being indicated in Figure 1 by dotted lines and by numeral 21. The said cut-out latter portion may after placing the tube therein be filled either by a wooden wedge, or 75 by plastic wood, or any other suitable material.

In case the tube system shown in Figure 6 is used, all that is necessary is to bore a hole centrally through the wooden block member for insertion of the arm 17 into the annular tube 80 member 15.

On top of the annular metal tube, when the latter has been placed in position in the block member, is next arranged a member 25 of any suitable material, preferably though a solid, semi-hard rubber member; the latter being secured to the said block member in any convenient manner, as for instance, by a cementing process. The said rubber member 25 is formed with openings 26 made to register with the apertures 20 in the metal tube, when the latter and the said rubber tube are arranged in relative position to one another.

In order, however, to derive the best possible effect from the said arrangement, the openings of the said rubber member have been formed with slightly outwardly tapered walls 27.

The block member 10 is upon its lower surface formed with cut-out portions 22, as shown in Figure 2, into which cut-out portions the bristles 13 are inserted; the said bristles being bent upon themselves and secured in the said cut-out portions by wedges 23, as shown especially in Figure 3; the said wedges being for this purpose formed with a slightly larger bottom portion, which in turn is slightly grooved, as shown at 24 in Figure 4.

It will be noted that the walls of the said grooved portions terminate in outwardly flaring 110 flanges, as indicated in dotted lines by 28.

The bristles 13 may, however, also be inserted into the recesses 29 of the wooden block-member, as shown in Figure 7. The bristles are in this latter case bent over the partitions 30, which are formed by transverse and vertical cut-out portions in the wooden block-member, as shown also in Figure 7, while the bristles are secured in place by a peripheral band 31, surrounding the edge of the said wooden block; the said band 31 being shown with parts broken away in Figure 7.

In the modification of my device, as shown in Figures 8, 9 and 10, a preferably metal frame structure is employed. The said frame structure comprises a circumferential ring-member 32, in the drawings shown of an oval shape. On top of this ring-member is arranged a longitudinal transverse metal bar 33, formed with a slight upward curvature. The said bar 33 is solidly connected to the ring-member 32 by being countersunk into rectangular bends formed upon the latter, as shown at 34, whereby a flush outer surface is attained.

The center portion of the wooden block member, as formerly described, that is the portion having the water-discharging arrangement, or tube-system, with the area of bristles within the periphery of the said tube, is, in this present modified arrangement of the features constituting my device, made to form an independent, detachable circular unit 35; the latter has an upper edge-portion 36, especially shown in Figure 10, adapted to engage the upper edge of the frame or ring-member 32, when placed in position, the said unit may be surrounded by a metal ring 37, as shown. The detail arrangement of features of the said circular unit 35, or central portion, is otherwise, as hereinbefore described; the said unit having in this case, however, a water-spout 38, as shown in Figure 8, connecting with the inlaid water-sprinkling system. The transverse bar 33 is made to rest in a transverse groove 39, shown in dotted lines, on top of the central block-member, or unit; while a band 40 of any suitable material is fastened to each side of the ring-member 32 and across the top of the circular unit to permit a varied manipulation of the device.

At each end of the said frame structure is detachably inserted a sponge member 41, which under normal conditions protrudes a little below the bristles of the central unit 35, and which fits snugly between the said frame member 32 and the said central unit. While the said sponge members on account their inherent elasticity will be retained in correct position in the said frame structure, suitable means may, however, be provided, if desired, to keep the said sponges solidly in place.

While, as stated in this modification, the central unit normally is provided with bristles inside of the water-sprinkling tube, the said unit may instead of such bristles have arranged therein a sponge-member, in any suitable manner.

The portion of the center part, which contains the bristles, that is the portion within the water sprinkling tube, and which is indicated by 42 in Figure 9, may, however, be made as a separate unit consisting of a thin disk, as shown in Figure 11, part thereof being broken away; said disk may in this case be arranged in a depression of a corresponding dimension formed in the said central portion; said depression being shown by dotted lines denoted 43 in Figure 8. The bristles of the center portion are in this case arranged in any suitable way in the middle thereof, while

slits 44 are shown at the periphery for attaching the bristles to the outer part of the said portion in a similar way as formerly described. A band 45 is in turn surrounding the said disk for holding the latter bristles in place.

Through this latter arrangement the central bristles may easily be exchanged, when worn out.

It is obvious that changes may be made in the form, construction and arrangement of the several parts, as shown, within the scope of the appended claims, without departing from the spirit of the invention, and I do not therefore wish to limit myself to the construction and arrangement shown and described herein.

What I claim as new, and desire to secure by Letters Patent of the United States, is:

1. A device of the class described, comprising a block member formed with a substantially flat bottom surface and having a circumferential groove therein, a perforated tube member disposed in the said groove, a rubber member, formed with openings therein to register with the perforations of the said tube, and mounted upon the latter, a plurality of bristles attached to the said bottom surface, and means for accomplishing said attachment.

2. A device of the class described, comprising a block member formed with a substantially flat bottom surface and having a circumferential groove therein, a perforated tube member disposed in said groove, a rubber member, formed with openings therein to register with the perforations of the said tube, and mounted upon the latter, the said bottom surface being formed with a plurality of substantially rectangularly shaped cut-out portions, bristles bent upon themselves and disposed in the latter, and means for securing said bristles in position.

3. A device of the class described, comprising a block member formed with a substantially flat bottom surface and having a circumferential groove therein, a perforated tube member disposed in said groove, a rubber member, formed with openings therein to register with the perforations of the said tube, and mounted upon the latter, the said bottom surface being formed with a plurality of substantially rectangularly shaped cut-out portions, bristles bent upon themselves and disposed in the latter, and wedged-shaped members inserted into the said cut-out portions for securing the bristles to the said bottom.

4. A device of the class described, comprising a block member formed with a substantially flat bottom surface and having a circumferential groove therein, a perforated tube member disposed in said groove, a rubber member, formed with outwardly flaring openings therein to register with the perforations of the said tube, and mounted upon the latter, the said bottom surface being formed with a plurality of substantially rectangularly shaped cut-out portions, bristles bent upon themselves and disposed in the latter, and wedged-shaped members grooved at their inner end and inserted into the said cut-out portions for securing the bristles to the said bottom surface.

5. In a device of the class described, a skeleton frame, a circular member detachably mounted within the latter, the said member having means for engaging the said skeleton frame, a water-sprinkling system arranged in the said member and bristles at the center of the latter; and sponge members mounted adjacent to the said circular member.

6. In a device of the class described, a skeleton frame, a member detachably mounted within the latter, the said member being formed with a substantially flat bottom surface and having a circumferential groove therein, a perforated tube member disposed in said groove, a rubber member, formed with outwardly flaring openings therein to register with the perforations of the said tube and mounted upon the latter, bristles arranged upon the central area of the said member, and sponge members mounted in the said skeleton frame, adjacent the first said member.

7. In a device of the class described, a skeleton frame, a circular member detachably mounted within the latter, the said member having means for engaging the skeleton frame, a water-sprinkling system arranged in the said member, a central disk detachably mounted in the latter and being provided with bristles upon its lower surface; and sponge-members arranged in the said skeleton frame adjacent to the circular member.
